UNITED STATES PATENT OFFICE.

BURT C. STEWART, OF DETROIT, MICHIGAN, ASSIGNOR TO MURPHY IRON WORKS, OF DETROIT, MICHIGAN, A CORPORATION OF MICHIGAN.

GRATE-BAR.

1,107,860.

Specification of Letters Patent. Patented Aug. 18, 1914.

Application filed January 16, 1914. Serial No. 812,563.

To all whom it may concern:

Be it known that I, BURT C. STEWART, a citizen of the United States of America, residing at Detroit, in the county of Wayne and State of Michigan, have invented certain new and useful Improvements in Grate-Bars, of which the following is a specification, reference being had therein to the accompanying drawings.

10 This invention relates to grate bars especially designed for that type of furnaces known as automatic stokers, wherein grates are disposed at an inclination and supplied with fuel by stoker boxes from fuel magazines located at the upper edges of the grates.

20 The primary object of my invention is to provide an inclined grate embodying stationary and movable sectional bars that are assembled and operate to effectually feed the fuel across and distribute the same evenly over the supporting surface of the grates and are so constructed as to provide for the 25 passage of air through the grates and insure a thorough combustion of fuel.

Another object of this invention is to provide a movable sectional grate bar for furnaces of the above type, wherein a plurality of bar sections are arranged end to end and 30 connected in such a manner that an undulatory movement is secured and in which the arrangement is such that they may be substituted for the grate bars as commonly constructed in this type of furnaces and are 35 adapted to be actuated by the means commonly employed for the purpose in such furnaces.

A further object of this invention is to provide a simple, durable and efficient construction, all as hereinafter more specifically described and claimed, reference being had to the accompanying drawings, wherein—

40 Figure 1 is a cross sectional view of a portion of a furnace provided with grate bars in accordance with my invention; Fig. 45 2 is a longitudinal sectional view of a portion of the furnace showing the grate bars in elevation; Fig. 3 is a side elevation of a 50 stationary grate bar; Fig. 4 is a bottom plan view of the same; Fig. 5 is a side elevation of a movable sectional bar in connection with a stationary bar; Fig. 6 is a plan

view of the same, and Fig. 7 is a cross sectional view taken on the line VII—VII of 55 Fig. 5.

In the drawings for the purpose of illustration, the invention is shown as embodied in an automatic stoker of an old and well known construction, but it will be understood that it is adapted for use in other types of furnaces and that such changes as may be necessary to conform thereto are contemplated as coming within the scope of 60 this invention.

A portion of a furnace is shown embodying a fuel magazine 1, stoker boxes 2, a coking plate 3, a grate bearer 4 and a rotary clinker grinder 5. The grate bearer 4 cooperates with the coking plate 3 in supporting stationary grate bars and movable 70 grate bars. The stationary bars are designated 6 and are alternately arranged relatively to the movable sectional bars. Each stationary bar has the upper end thereof 75 provided with supporting lugs 7 that rest against the coking plate 3 and serve as spacers for the upper ends of the stationary bars. The lower end of the stationary bar is enlarged, as at 8 and provided with a 80 hook-shaped lug 29 that engages a side wall of the bearing 4. The hook-shaped lugs 29 also serve as spacers for the lower ends of the stationary bars and each lower end has a sector-shaped opening 9 and side shields 85 10. The side walls of the stationary bar 6 are cut away at the lower edge of said bar to form a longitudinal web 11 and the sides of said web are provided with spaced guide 90 bosses 12. The side walls of the bar, above 95 the web 11, are provided with sets of transverse openings 13 and with equally spaced angularly disposed ribs 14. The ribs between the sets of openings 13 extend from the upper edge of the bar to the upper edge 95 of the web 11 and the remaining ribs are of a less length and provide clearance for the openings 13. The upper end of the stationary bar, at one side thereof, is provided with a pivot pin 15, the purpose of which 100 will presently appear.

Each movable bar comprises a plurality of longitudinally alining sections 16 of a less depth than the stationary bar 6 and their combined length is approximately that 105 of a stationary bar. The sections 16 have

the sides thereof cut away, as at 17 to save material and reduce the weight of each section, and one end of each section has a rocker extension 18 and the opposite end thereof a 5 socket 19, said sockets receiving the extensions 18, as best shown in Fig. 5. The ends of the sections 16, at the upper edges thereof are beveled as at 20, to permit of ashes and other matter easily passing between the 10 movable and stationary bars, and to normally maintain the upper edges of the sections 16 in the same plane as the upper edges of the stationary bars 6 the sections 16 are provided with sets of transverse openings 21 15 to receive sectional pivot rods 22 that extend into or through the openings 13 of the stationary bar 6. The sectional pivot rods 22 facilitate assembling the grate bars and by providing sets of openings in said bars it is 20 possible to change the location of the pivot rods and consequently the action of the movable bars and also to substitute other sections of different relative lengths or to increase or decrease the number of sections 25 used in connection with each movable grate bar.

The lower section of each movable grate bar has a notch and a channel shaped rim 23 to receive the rocker 24 of a rocker bar or 30 shaft 25, which extends through the openings 9 of the stationary bars 6.

The upper section of each movable grate bar has a slot or elongated opening 26 to receive the pivot pin 15 of the stationary bar, 35 said pin extending through the opening 26 and into a recess provided therefor in an adjoining stationary grate bar.

Any suitable means may be employed for operating the rocker bar or shaft 25, which 40 is limited in its movement by the upper and lower walls of the openings 9 of the stationary bar 6. The shields 10 of the stationary bar 6 prevent clinkers and other matter from interfering with the operation of the 45 rocker bar or shaft 25. When the rocker bar or shaft 25 is placed in operation an undulating or wave like movement is imparted to the sections of a movable grate bar throughout its length by reason of said sections being pivotally mounted upon the rods 22 and their confronting ends connected by the rocker extensions 18. The confronting ends of the sections are beveled or cut away sufficiently to permit of the sections rocking 50 and as the ends of the sections are raised and lowered relatively to the upper surfaces of the stationary grate bars, the fuel supported thereby is agitated and distributed and at the same time is caused to travel slowly 55 down the inclined grate toward the clinker grinder, receiving the requisite amount of air through the grate to complete the burning process. By the time the fuel reaches the clinker grinder the combustion is complete 60 and the ash and other residue are auto- 65

matically removed and deposited in the ash pit.

The sections of the movable grate bars are prevented from becoming accidentally displaced or wabbling upon the pivot rods 22 70 by the guide bosses 12 and these bosses are so disposed that they serve their purpose in the various positions of adjustment of the movable sections of the bars. As illustrated in Fig. 5, the movable sections are positioned 75 for a minimum action relatively to the stationary bars, but by shifting the pivot rods 22 to other openings of each set a maximum action may be obtained, and it is through the medium of this adjustment that the 80 highest efficiency is obtained and certain conditions met with at the time of installation.

The manner of articulating the sections of each movable grate bar and imparting 85 movement thereto from one end of the bar gives a positive motion which evenly distributes the fuel and imparts an even feed thereto, keeping the grate clear to allow free passage of air through all parts thereof, thus 90 assuring a complete combustion of fuel and a rapid discharge of ash and clinkers.

It is thought that the operation and utility of the grate bars will be apparent without further description, and while in the drawings there is illustrated a preferred embodiment of my invention, it is to be understood that the structural elements are susceptible to such variations and modifications as fall within the scope of the appended claims.

What I claim is:—

1. A grate comprising spaced stationary bars, and articulated bar sections pivotally supported by said stationary bars between 105 said stationary bars and adapted to have movement imparted thereto at one end of one of said sections.

2. A grate comprising stationary spaced bars, bar sections, pivot pins carried by each bar section and extending from said stationary bars to pivotally support said bar sections between said stationary bars, and means for imparting an undulatory movement to said bar sections throughout the 110 length of said stationary bars.

3. A furnace grate comprising alternately arranged inclined, stationary and movable grate bars, each movable bar having a plurality of pivotally supported articulated sections, and means at one end of said bars for imparting an undulatory movement to said movable bars throughout their length. 115

4. A furnace grate comprising alternately arranged, inclined, stationary and movable bars, each movable bar having articulated sections, means for pivotally supporting the sections of each movable bar whereby their movement between said stationary bars is regulated, and means at the lower ends of 120 125 130

said movable bars for imparting an undulatory movement to said bars throughout their length.

5. A furnace grate comprising alternately arranged inclined, stationary and movable bars, guide bosses carried by the sides of said stationary bars, each movable bar having a plurality of pivoted articulated sections bearing against said bosses, and a 10 rocker bar imparting an undulatory movement to all of said movable bars.

6. A furnace grate comprising stationary bars, pivot rods capable of adjustment therein, articulated bar sections capable of adjustment upon said rods, and means for imparting an undulatory movement to said bar sections.

7. A furnace grate comprising a series of stationary grate bars and a series of movable bars alternating with said stationary bars and supported thereby, each movable bar comprising a series of articulated sections with each section pivotally supported intermediate its ends upon the stationary bars, 25 and means engaging an end section of each movable bar for actuating the several sections of the several movable bars.

8. A furnace grate comprising a series of stationary grate bars, means for spacing 30 said bars apart, a series of movable grate bars, each comprising a plurality of articulated sections pivotally supported with-

in the spaces between the stationary bars to turn freely therein, said stationary bars and sections being formed with transverse 35 openings, and pivot rods extending through said openings in a plurality of said bars and sections to pivotally and detachably support said sections upon said stationary bars.

9. A furnace grate comprising a series of stationary bars rigidly supported at their ends and spaced apart, a series of movable bars alternating with the stationary bars and each comprising a series of sections each having a transverse opening intermediate 40 its ends and a notch at one end to receive a projection on the adjacent end of the next section to transmit motion from one section to another, said stationary bars being each formed with a group of transverse 45 openings adjacent to each section of the movable bars, pivot rods engaging the openings in the stationary bars and sections to pivotally support the sections intermediate their ends, and a rocker member to engage 50 the notch in one of the end sections of each movable bar.

In testimony whereof I affix my signature in presence of two witnesses.
